FIREARMS

Louis Stiennon, deceased, late of New Haven, Conn., by Roy L. Parsell, administrator, Pine Orchard, Conn., assignor to Winchester Repeating Arms Company, New Haven, Conn., a corporation of Maryland

Application June 20, 1935, Serial No. 27,517

12 Claims.

(Cl. 42—40)

This invention relates to improvement in firearms, and more particularly to the cover-plate trigger-guard features thereof.

One of the objects of the present invention 5 is to provide a superior firearm structure in which the cover-plate for the bottom frame-opening may be conveniently secured in place and removed.

A further object is to provide a firearm structure 10 in which the securing in place of the bottom cover-plate is effected by and dependent upon the trigger-guard.

With the above and other objects in view, as will appear to those skilled in the art from the 15 following, considered in conjunction with the accompanying drawing and appended claims, the present invention includes all features disclosed therein which are novel over the prior art.

20 In the accompanying drawing:

Fig. 1 is a broken view mainly in side elevation and partly in vertical central section of a firearm in which the present invention is incorporated;

25 Fig. 2 is a broken under-side view thereof with the locking-stud shown in section;

Fig. 3 is a broken transverse sectional view taken on the line 3—3 of Fig. 1;

30 Fig. 4 is a similar view taken on the line 4—4 of Fig. 1;

Fig. 5 is a broken perspective view of the frame viewed mainly from the under-side thereof;

Fig. 6 is a perspective view of the trigger-guard unit; and

35 Fig. 7 is a perspective view of the cover-plate or closure.

For the purpose of illustrating the present invention, a breakdown firearm has been shown in the accompanying drawing, which firearm includes, as is usual, a butt-unit and a barrel-unit. The butt-unit comprises in the main a frame generally designated by the numeral 10, and a buttstock 11 secured to its rear end. The barrel-unit comprises in the main one or more barrels 40 12 and a forestock 13, the shoe 14 of which latter bears against the cylindrically-contoured forward end 15 of the frame 10 much in the usual manner of breakdown firearms.

The frame 10 has rearwardly projecting from 45 its upper and bottom walls respectively a pair of substantially-parallel spaced-apart tangs 16 and 17. The respective rear ends of the tangs 16 and 17 just referred to are coupled together in spaced relationship by a substantially-vertical 50 spacing-block 18 into which is threaded a butt-

stock-bolt 19 serving to secure the buttstock 11 in place.

Directly below its forwardly-facing standing-breech 20 the frame 10 is provided with a bottom-passage 21 closed by a removable cover-plate 5 or closure 22 and through which various machining operations may be carried on within the interior of the frame, and through which features of the mechanism may be introduced, removed and adjusted. The under-surface of the 10 portion of the frame around the bottom-passage 21 is cut or otherwise shaped to provide a recess 23 and a substantially-continuous downwardly-facing ledge 24. The cover-plate 22 snugly fits the recess 23 just described and is so proportioned that when the edge of its upper face is engaged with the ledge 24, its bottom surface will be flush with the bottom surface of the frame 10.

In the forward wall of the recess 23, the frame 10 is formed with an undercut coupling-recess 20 25, resulting in the formation of a rearwardly-projecting coupling-lip or projection 26 engageable by a coupling-lip 27 forwardly offsetting from the forward end of the cover-plate 22. Formed integral with and rearwardly-projecting from the cover-plate 22 is a locking-finger 28 having its upper rear corner notched as at 28a. The locking-finger 28 laterally snugly fits the forward end of the contracted lower portion of a groove-like T-shaped socket 29 formed in 30 the under face of the frame 10 and its bottom tang 17 just rearwardly of the bottom-opening 21 and intersecting the recess 23.

The T-shaped groove or socket as thus located provides on its respective opposite sides 35 30—30, a pair of complementary locking-ledges 30—30, with the respective upper faces of which is adapted to engage the respective under faces of a pair of complementary locking-fingers 31—31 of a T-shaped locking-stud 32 having a cylindrical body portion 31a.

To accommodate the cylindrical body portion 31a of the locking-stud 32, the complementary ledges 30—30, which in a sense overhang the wide part of the groove or socket 29 in the frame, are 45 notched as at 33 so that the said groove or socket, viewed from the under-side of the firearm, presents a keyhole-shaped appearance. It will be noted, by reference to Fig. 6 in particular, that the head of the locking-stud 32, the opposite ends 50 of which provide the locking-fingers 31—31, is narrower than the cylindrical portion of the said locking-stud, and may readily be inserted into and removed from the socket or groove 29 through the relatively-narrow bottom portion thereof.

The locking-stud 32 before described vertically offsets from the forward end of a trigger-guard 35 having an upwardly-facing locking-ledge 34 which normally extends beneath the under-face 5 of the locking-finger 28 of the cover-plate 22 and holds the rear end of the latter in the recess 23. The said trigger-guard 35 is located on the under-side of the firearm and is provided with a rearwardly-extending tang 36 secured to the under-face of the buttstock 11 by means of a screw 37. The loop-shaped forward portion of the trigger-guard 35 serves to outline a space in which a trigger 33 rocks, which trigger is pivotally connected to the bottom tang 17 by means of the 15 transverse pivot-pin 38 extending thereacross.

As shown, the cover-plate 22, in addition to serving as a closure for the bottom-opening 21 in the frame 10, is provided with an upwardly-opening shallow socket 40 receiving the lower end of 20 a helical spring 41, which exerts an upward thrust upon a latch-member 42 mounted in the frame 10 just to the rear of the standing-breech 20 thereof.

Should it be desired to remove the cover-plate 25 22 for any reason, after the same has once been installed in place, the screw 37 may be removed to thus free the trigger-guard 35 for lateral pivotal movement about its locking-stud 32. When the trigger-guard is turned so that it projects at 30 a right angle from the gun structure, rather than extending parallel therewith, as is normal, the locking-fingers 31—31 of the locking-stud 32 are "unhooked," so to speak, from the locking-ledges 30—39 of the T-shaped groove or socket 29, thus 35 permitting the stud to be withdrawn downwardly from the said groove, bringing with it the coupling-finger 28 of the bottom-plate 22. As the trigger-guard unit, comprising the parts 31, 31^a, 32, 34, 35 and 36, is removed from the gun-structure 40 as above described, the bottom-plate 22 will pivot about its coupling-lip 27 and assume substantially the position in which it is shown by broken lines in Fig. 1, from which position it may 45 be removed from the gun structure by moving it rearwardly to disengage its coupling-lip 27 from the undercut coupling-recess 25.

When it is desired to replace the cover-plate 22, the gun may be inverted and the said plate positioned in the recess 23. If, now, the trigger-guard is turned so as to extend at a right angle 50 with respect to the gun structure and one of its locking-fingers 31 placed in the notch 28^a above the coupling-finger 28, both of the said coupling-fingers may be passed through the contracted 55 lower portion of the groove 29 into the relatively-wide upper portion thereof, so that upon the turning the trigger-guard into its normal position, the said locking-fingers 31—31 will "hook over," so to speak, the upwardly-facing locking-ledges 30— 60 30 formed at the respective opposite sides of the said groove 29.

Thus, the cover-plate 21 will be held at its forward end against downward displacement by the entry of its coupling-lip 27 into the undercut 65, 25 and its rear end will be held in place by the locking-ledge 34 on the trigger-guard 35, which will, at this time, underlie a portion of the under-face of the coupling-finger 28. If, now, the screw 37 is passed through the tang 36 of the trigger-guard 70 and screwed into the buttstock 11, the trigger-guard will thus be held against lateral swinging movement and both the said trigger-guard and the said cover-plate firmly held in place against accidental displacement.

75 The invention may be carried out in other spe-

cific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein. 5

What is claimed:

1. A firearm construction, including: a frame 10 having a passage therein; a closure for the said passage; and a trigger-guard unit physically distinct from the said frame and removable therefrom; the said trigger-guard unit having a portion serving to hold the said closure in closing 15 position with respect to the passage in the said frame when the said trigger-guard unit is itself in assembled position on said frame.

2. A firearm construction, including: a frame 20 having a passage therein; a closure for the said passage; and a trigger-guard unit physically distinct from the said frame and removable therefrom, and having a portion overlapping a portion of the said closure and serving to hold the same in place when the said trigger-guard unit is itself in 25 assembled position on said frame.

3. A firearm construction, including: a frame having a passage therein and provided with a coupling-recess adjacent the latter; a closure for the passage in the said frame and having a portion extending into the coupling-recess of the latter; and a trigger-guard unit physically distinct from the said frame and removable therefrom, and having a portion serving to hold the said closure in closing position with respect to 35 the passage in the said frame when the said trigger-guard unit is itself in assembled position on said frame.

4. A firearm construction, including: a frame 40 having a passage therein and provided with a coupling-recess adjacent the latter; a closure for the passage in the said frame and having a portion extending into the coupling-recess of the same; and a trigger-guard unit physically distinct from the said frame and removable therefrom, and having a portion overlapping a portion 45 of the said closure and serving to hold the same in place when the said trigger-guard unit is itself in assembled position on said frame.

5. A firearm construction, including: a frame 50 having a passage therein and also having a socket shaped to provide a locking-ledge; a closure for the passage in the said frame; and a removable trigger-guard unit provided with a locking-finger engageable with the locking-ledge 55 of the said frame; the said trigger-guard unit having a portion serving to hold the said closure in place when the said trigger-guard unit is itself in assembled position.

6. A firearm construction, including: a frame 60 having a passage therein and also having a socket shaped to provide a locking-ledge; a closure for the passage in the said frame; and a trigger-guard unit physically distinct from the said frame and removable therefrom, and having a portion overlapping a portion of the said closure and serving to hold the same in place when the said trigger-guard unit is itself in assembled position on said frame.

7. A firearm construction, including: a frame 70 having a passage therein and also having a socket shaped to provide two oppositely-located locking-ledges; a closure for the passage in the said frame; and a removable trigger-guard unit provided with a pair of complementary locking- 75

5 fingers engageable with the oppositely-located locking-edges of the said frame; the said trigger-guard unit having a portion serving to hold the said closure in place when the said trigger-guard unit is itself in assembled position.

8. A firearm construction, including: a frame having a passage therein and also having a socket shaped to provide two oppositely-located locking-edges; a closure for the passage in the said frame; and a removable trigger-guard unit provided with a pair of complementary locking-fingers engageable with the oppositely-located locking-edges of the said frame; the said trigger-guard unit having a portion engaging a portion 10 of the said closure and serving to hold the same in place in the said frame when the said trigger-guard unit is itself in assembled position.

9. A firearm construction, including: a frame having a passage therein and provided with a coupling-lip adjacent the same; a closure for the passage in the said frame and having a portion engaged with the coupling-lip of the latter; and a removable trigger-guard unit provided with a pair of complementary locking-fingers engageable with the oppositely-located locking-edges of the said frame; the said trigger-guard unit having a portion serving to hold the said closure in place when the said trigger-guard unit is itself in assembled position.

10. A firearm construction, including: a frame having a passage therein and provided with a coupling-recess adjacent the same; a closure for the passage in the said frame and having a portion extending into the coupling-recess of the

latter; and a removable trigger-guard unit provided with a pair of complementary locking-fingers engageable with the oppositely-located locking-edges of the said frame; the said trigger-guard unit having a portion overlapping a portion 5 of the said closure and serving to hold the same in place in the said frame when the said trigger-guard unit is itself in assembled position.

11. A firearm construction, including: a frame having a passage therein and also having a 10 groove-like socket intersecting the said passage and shaped to provide a pair of complementary locking-edges; a closure for the passage in the said frame; and a removable trigger-guard unit having a locking-stud offsetting therefrom, which 15 locking-stud includes a substantially-cylindrical portion and a pair of complementary offsetting locking-fingers respectively engageable with the locking-edges of the groove in the said frame; a portion of the said trigger-guard unit having 20 a portion engaging with a portion of the said closure and holding the same in place.

12. A firearm construction including in combination: a frame having a passage therein; physically distinct from the said frame and removable therefrom, and a closure for the said 25 passage; and a trigger-guard having a portion serving to hold the said closure in closing position with respect to the passage in the said frame when the said removable trigger-guard is in its 30 normal position on the firearm structure.

ROY L. PARSELL,
Administrator of the Estate of Louis Stiennon,
Deceased.
